J. K. Lum,

Wind Wheel,

N° 21,472.

Patented June 21, 1859.

Inventor,
James R. Lum

UNITED STATES PATENT OFFICE.

JAMES K. LUM, OF SKOOKUMCHUCK, WASHINGTON TERRITORY.

IMPROVEMENT IN WINDMILLS.

Specification forming part of Letters Patent No. 24,472, dated June 21, 1859.

To all whom it may concern:

Be it known that I, JAMES K. LUM, of Skookumchuck, in the county of Thurston and Territory of Washington, have invented a new and Improved Arrangement of Means for Applying Wind as a Motive Power; and I do hereby declare that the following is a full, clear, and exact description of the same, reference being had to the annexed drawings, making a part of this specification, in which—

Figure 1 is a side view of my invention, the framing being in section; Fig. 2, a detached view of the ratchet device and "fly" by which the power of the wind-wheel is made to actuate or raise the weight.

Similar letters of reference indicate corresponding parts in the two figures.

The object of this invention is to obtain a more equitable or uniform motion than has hitherto been done by the use of a wind-wheel, and at the same time effect a saving in power; or, in other words, employ all the power of the wheel, so that the same may be laid up in reserve to be used when required.

The invention consists in having a weight connected with the wind-wheel in such a way that the same will be raised by the rotation of the wheel and made to actuate or drive machinery by its descent when the wheel is stopped, the wind-wheel being employed to raise the weight only instead of being directly connected with the machinery, as heretofore.

To enable those skilled in the art to fully understand and construct my invention, I will proceed to describe it.

A represents a framing, which may be constructed in any proper manner to support the working parts. On the top of the framing A a cap B is placed and so fitted to the framing that it may rotate freely thereon. To the cap B a vane C is attached, and a shaft D is also placed in said cap in line with the vane C. The shaft D is allowed to rotate freely in the cap B, and a crank a is on said shaft, said crank being within the cap.

On the outer end of the shaft D a hub b is attached, said hub having a series of radial arms c attached, on each of which a sail or wing d is placed loosely or so that it may turn freely thereon. These sails or wings are connected by rods e with a sliding collar f on the

shaft D, which collar is connected by a rod g with a bent-lever frame h, placed in the cap B and connected with a spring a^x.

In the upper part of the framing A a vertical slide E is placed, said slide having two pendants i, j attached. The lower end of the pendant i is connected to a lever F, which is secured in the framing A by a fulcrum-pin k.

To the crank a of the shaft D a connecting-rod G is attached, the lower end of which is connected to the upper part of a bent-lever H, which has its fulcrum at l. The lower end of the lever H has two pawls m, n attached to it, said pawls engaging with a ratchet o, which is secured to the bottom of a fly or frame I, which is fitted loosely on a vertical arbor J in the lower part of the framing A. The pawl m is hooked at its end and actuates the ratchet with a pull or draw movement, while the pawl n actuates the ratchet with a thrust or shoving movement. The two pawls are kept in contact with the ratchet by a spring p. This will be clearly understood by referring to Fig. 2.

To the lower end of the arbor J a toothed wheel q is attached. This wheel gears into a pinion r, which is on the inner end of a horizontal shaft s, said shaft having a toothed wheel t on its outer end. The wheel t is provided with two sets of gears u, v, one of which u engages with the pinion w of a governor-shaft x, the other v gearing into the pinion y of a shaft z, having a balance-wheel a' on its outer end. The governor K may be of usual construction, and it has a lever L connected with its upper end, said lever having a weight b' on its outer end. To the lever L a rod c' is attached, the lower end of which is connected with a brake d', that acts against the periphery of the balance-wheel a'. The power is taken from the shaft z or s. M is a shaft around which a cord or rope N is wound, and this cord or rope passes upward and is connected to one end of the lever F. (See Fig. 1.)

The fly or frame I may be described as being formed of a circular disk e', with two uprights f', f' attached, connected at their upper ends by a cross-piece g'. This fly is allowed to rotate freely on the arbor J, and in each upright f' a pulley h' is placed, around which the ends of a cord i' pass, the two ends of said cord being wound on the arbor J in

reverse directions, so that both ends will, as the fly rotates, be wound simultaneously on the arbor J. The cord i' passes through a sheave j', which is attached to a cord or rope W, that passes over a pulley O in the upper part of the framing, the cord W passing through the end of lever F opposite to the end where the cord N is attached, and having a weight P attached to its end.

A' is a shaft having a projection B attached to its end at right angles, which projection bears against the wheel a' and prevents the rotation of the same and machinery connected with it when it is not required to operate.

The operation is as follows: Suppose the machine to be at rest and a sufficient wind blowing to drive it. The attendant, in order to put the machine in motion, turns the shaft M by hand to slacken the cord N, and the spring a^x will present the sails or wings d to the wind in consequence of actuating the sliding collar f. The wind-wheel will then commence to rotate, and the cord i' will, in consequence of the action of the rod G, lever A, pawls m n, and ratchet o, and fly-wheel I, be wound on the arbor J. When the wind-wheel commences to rotate, the machine may be driven, if desired, the shaft A' being turned so as to free the projection B' from the wheel a'. If the power of the wind is more than sufficient to preserve a certain uniform motion, the weight P continues to go up, and, on reaching the lever F,

actuates it so as to turn the sails d through the medium of the pendant i, lever h, and sliding collar f, so that the speed of the wheel will be checked. The wind-wheel, it will be seen, may be constantly changing its velocity or stop, but the machinery continues to be driven so long as the weight P is up. No power, therefore, is lost, except the surplus, and that is not needed. The object of the governer is to overcome the increase of power exerted upon the machinery in consequence of the constantly varying inertia of the weight P.

I do not claim a wind-wheel provided with adjustable sails or wings d, nor do I claim a governor K nor brake-wheel a, for these devices are old and well known; but,

Having described my invention, what I do claim as new, and desire to secure by Letters Patent, is—

The employment or use of the fly or frame I, placed on the arbor J and having the ends of the cord i passing through it and attached to said arbor, said cords being also attached to the rope W of the weight P, the fly being operated by the wind-wheel in such a manner as to admit of a simultaneous rotation of the arbor J.

JAMES K. LUM.
